UNITED STATES PATENT OFFICE

EDWARD H. LORENZ, OF WEST HARTFORD, CONNECTICUT, ASSIGNOR TO HARTFORD-EMPIRE COMPANY, OF HARTFORD, CONNECTICUT, A CORPORATION OF DELAWARE

LEER LOADER

Application filed July 12, 1926. Serial No. 121,750.

My invention relates to apparatus that is particularly suitable for use in transferring glassware to leers, but is capable of employment in various other relations where it is desired to transfer articles from one point to another.

My invention has for one of its objects the provision of a simplified and improved form of ware handling mechanism.

Another object of my invention is to provide mechanism that is capable of transferring articles from a given point to a receiving surface, and of depositing the articles on the receiving surface in predetermined spaced relation and aligned in a direction substantially transverse to the line of movement of the ware to the receiving surface.

Another object of my invention is to provide a plurality of transfer mechanisms combined to operate as a unit to transfer articles to a leer conveyer or other surface without interference with one another.

Some of the forms which my invention may take are shown in the accompanying drawings wherein Fig. 1 is a side elevational view of apparatus embodying my invention; Fig. 2 is a plan view thereof; Fig. 3 is an enlarged vertical sectional view of the apparatus of Fig. 1; Fig. 4 is a view on a still larger scale of tong mechanism which I employ; Fig. 5 is a view taken on the line 5—5 of Fig. 4; Fig. 6 is a vertical sectional view of a portion of the ware gripping mechanism shown in Fig. 1; Fig. 7 is a view taken on the line 7—7 of Fig. 3, but on an enlarged scale; Fig. 8 is an enlarged detailed view of a portion of the apparatus of Fig. 1, looking from the rear side thereof; Fig. 9 is a view taken on the line 9—9 of Fig. 8; Fig. 10 is a view showing a modified form of apparatus wherein the transfer mechanisms form a unitary structure but transfer ware from separate conveyers to a leer; and Fig. 11 is a sectional view showing one of the yielding elements which I employ in two of the pull chains.

For convenience of illustration, and referring to Figs. 1 to 9, I have shown my apparatus as arranged for transferring bottles or other ware from a conveyer 15 that delivers

ware from a glass-blowing machine (not shown) or other source, to a leer conveyer belt 16 by which the ware is carried into a leer 17 for annealing.

Above the adjacent ends of the conveyers 15 and 16, I mount a framework 18 that carries a bracket 19 which is provided with bearings 20 and 21 for a swivelled or oscillatory frame 22.

The frame 22 carries a pair of depending arms 23 and 24. A shaft 25 is mounted in the swinging frame 22 and supports cranks 27 and 28, and a sprocket wheel 29. One end of a chain 30 is connected to the sprocket wheel 29 and the chain passes around the sprocket wheel and through a sleeve forming part of bearing 21, from whence it extends around a sprocket wheel 31. The end of the chain 30 is connected to a piston rod 32 that carries a piston 33 which is disposed in a cylinder 34. A pipe 35 is provided for conducting fluid pressure to the lower end of cylinder 34, from any suitable source (not shown), to move the piston 33 and cause the chain to be drawn over the sprocket wheels 29 and 31 to rotate them. Fluid pressure may also be supplied to the upper end of the cylinder 34, if desired, to make the return stroke of the piston 33 more rapid and thereby increase the speed of the apparatus.

Referring now more particularly to Figs. 3 and 7, when the chain 30 is operated to rotate the sprocket wheel 29 in a clockwise direction, the crank 27 will be turned to exert an upward pull upon a chain 36 that passes around a sprocket wheel 37 which is secured to a swinging arm 38. The arm 38 has ball bearing support upon a shaft 39 which is mounted in the lower end of the arm 23. The arm 38 will thus be swung in a clockwise direction about the shaft 39 as an axis, carrying with it ware gripping tongs 40. The ware gripping tongs 40 are carried by a sleeve 41 which is attached to a shaft 42 by means of clamping members 43. The shaft 42 is journaled in the outer end of the arm 38 and has a sprocket wheel 44 secured thereto. A chain 45 passes around the sprocket 44 and a sprocket wheel 46 that is secured to the fixed

shaft 39 so that the wheel 46 will not have rotative movement about its center.

It will be seen that when an upward pull is exerted by the crank 27 upon the chain 36, 5 the arm will be swung in a clockwise direction about its pivot 39, and the sprocket wheel 44, by reason of its connection to the non-rotatable sprocket wheel 46, will be given a planetary movement. In other words, the 10 shaft 42 which carries the sleeve 41 and the tongs 40 will be rotated in a counter-clockwise direction with respect to the arm 38, sufficient to maintain the sleeve 41 in a vertical position and prevent idle swaying movement of the tongs and a bottle carried thereby, while being moved from one position to another. Movement of the chain 36 is continued until the sprocket wheel 37 has rotated 180 degrees, whereupon the arm 38 will 15 20 occupy the position indicated in dotted lines in Fig. 3, at which position the tongs 40 will be caused to grasp a bottle, by mechanism which will be now described.

The tongs 40 (Figs. 4 and 6) are pivotally supported from a cylinder 48 that is secured to the sleeve 41. A pin 49 extends through arms 50 and 51 of the tongs 40, so that movement of one tong about its pivot will cause the other tong to have a corresponding movement. The tongs 40 are normally held in contracted or closed position (Fig. 4) by a spring-pressed plunger 52, the pressure of which can be adjusted by a screw 53 which bears against a compression spring 54 that 30 35 extends into the plunger 52.

Opening movement of the tongs 50 is effected by a piston 55 to the upper side of which fluid pressure is admitted past a piston rod 56 to which the piston is connected. A 40 suitable choke valve may be used, if desired, to control the admission of pressure above the piston 55. The piston rod 56 is normally held in its uppermost position by a compression spring 57 (Figs. 4 and 6). The extent 45 to which the tongs 50 can close is regulated by means of a screw 57^a which engages the top of the piston rod 56, as shown in Fig. 6.

Fluid pressure for effecting downward movement of the piston 55 and opening of the 50 tongs 40 is supplied through a pipe 58 (Fig. 7) which leads from any suitable source of pressure (not shown). Fluid pressure from the pipe 58 flows through a conduit 59 in the shaft 39 from whence it flows through a radial passage to the space surrounding a reduced portion 60 of the shaft 39, and thence through a port in the sleeve 61 to a pipe 62 that is disposed in the arm 38 and communicates at its outer end with a recess that surrounds the sleeve 63. The sleeve 63 is provided with a radial passage that leads to an annular recess around a reduced portion 64 of the shaft 42 from whence a port leads into the sleeve 41, so that the air or other fluid

may flow past the piston rod 56 to the piston 55.

In swinging the arm 38 to the position indicated by dotted lines in Fig. 3, the rear end of the chain 36, which is connected to a piston rod 66 is drawn downward, drawing with it a piston 67 that fits within a cylinder 68. Air pressure is constantly maintained in the cylinder 68 under the piston 67, and is admitted through a pipe 69. The piston 67 thus serves to cushion the movement of the arm 38. To return the arm 38 from the position indicated by dotted lines in Fig. 3 to that indicated by full lines, the air supply through pipe 35 (Fig. 1) is exhausted and the air pressure in the cylinder 68 raises the piston 67 and thereby moves the sprocket wheel 37 in a counter-clockwise direction.

The crank 28 (Fig. 1) is connected to a chain 71 that passes around a sprocket wheel 72 which is connected to an arm 73 that corresponds to the arm 38 and carries at its outer end a sprocket wheel 74 which corresponds to the sprocket wheel 44. The arm 73 carries tongs 75 that are operated in the same manner as the tongs 40. The forward end of the chain 71 is connected to a piston rod 76 that extends into a cylinder 77 which is similar to the cylinder 68. When the crank 28 is swung in a clockwise direction by movement of the piston 33, from the position shown in Fig. 1, the arm 73 is swung in a counter-clockwise direction to transfer a bottle from the conveyer 15 to the leer conveyer 16, and return movement of the arm 73 is effected by fluid pressure maintained in the cylinder 77 which contains a piston (not shown) that is connected to the piston rod 71. The tongs 75 are maintained in substantially vertical alignment, by means of a chain 79 that passes over a fixed sprocket wheel 80 which corresponds to the sprocket wheel 46 of Fig. 7.

The admission of fluid pressure to the operating pistons 55 of the tongs 40 is so timed that when the arms 38 and 73 are swung to approximately the positions indicated in full lines in Fig. 3, the piston 55 will be moved downward spreading the tongs 40 against the tension of the spring 54 and releasing the bottle. When the arms are moved to the position corresponding to that indicated by dotted lines in Fig. 3, the said pressure is cut off and the spring 54 contracts the tongs against a bottle so that the bottle may be carried to the leer conveyer.

The point at which the bottles are removed from the conveyer 15 is directly beneath the axis of the swinging frame 22 (Figs. 1 and 3), and the arms 38 and 73 have their axes angularly disposed relative to one another in such manner that when swung rearwardly to pick up a bottle from the conveyer 15 the tongs will be directly beneath the axis of the frame 22, while when swung forwardly they will deposit the bottles at different locations lat-

erally of the conveyer 16. The arms when at either extreme of movement are relatively offset about their axes a distance of 180 degrees, so that when one arm is depositing a bottle upon the leer conveyer 16, the other arm will be lifting a bottle from the conveyer 15, and there will be no interference between the arms during movements thereof.

The leer conveyer 16 ordinarily moves quite slowly and it is desirable to place a maximum number of bottles thereon. For this reason, means are provided for oscillating the arms 38 and 73 transversely of the conveyer 16, so that the arm 38 will deposit bottles across substantially one-half the width of the conveyer 16, and the arm 73 will distribute bottles across the remaining half.

In order to effect this lateral distribution of bottles upon the conveyer 16, the frame 22 is oscillated in a horizontal plane by means of a cam member 83 that is secured to a shaft 84 and has a peripheral slot that engages a cam roller 85 which is carried by an extension 86 of the frame 22, so that as the cam is rotated the forward end of the frame 22 will oscillate transversely of the conveyer 16.

The cam member 83 is driven from a pinion 87 (Figs. 8 and 9) that is secured to a shaft 88 and meshes with a gear wheel 89 which in turn has driving engagement with a gear wheel 90. The gear wheel 90 meshes with a gear wheel 91 that is secured to the shaft 84 upon which the cam member 83 is mounted. A ratchet wheel 92 is secured to the shaft 88 and is intermittently rotated by a pawl 93 which is secured to a sleeve 94 that carries the sprocket wheel 31 around which the chain 30 passes. When the piston 33 is moved toward the upper end of the cylinder, it effects rotation of the sprocket wheel 31 and causes the pawl to rotate the ratchet wheel 92 and the cam member 83. By reason of the gear reduction between the ratchet 92 and the cam member, the movement of the cam member is slight and hence the frame 22 is swung only a sufficient distance to permit a bottle to be deposited adjacent to a bottle previously deposited upon the leer conveyer 16. The intermittent movement or indexing of the cam member 83 is such that during each dwell, two bottles will be transferred from the receiving position on the conveyer or buck 15 to the leer conveyer 16. This is due to the fact that the indexing of the cam is effected by the pawl and ratchet device 92 to 93 above described, which causes the cam 83 to be moved one step for each complete cycle of the apparatus during which each arm makes a complete two-way oscillation.

As will be seen from Fig. 2, the cam 83 is designed to cause a step-by-step movement first in one direction transversely of the receiving conveyer 16, then in the opposite direction, the steps of the cam 83 being such that the dwells occurring during movement

in one direction are offset with respect to the dwells occurring during movement in the opposite direction. Through this arrangement, bottles are deposited properly upon the slowly moving continuous conveyer, so as to most efficiently occupy the conveyer space. As the cam 83 moves the carriage in one direction, bottles are deposited in spaced relation across the conveyer, and as it moves the carriage in the opposite direction, other bottles are deposited substantially in the spaces between the first mentioned bottles. When the chain 30 is returned to the position shown in Fig. 1, the pawl 93 will slide over the tooth of the ratchet 92.

When it is desired to vary the length of stepped movements of the swinging frame 22 so that articles of different sizes may be compactly placed upon the leer conveyer, without excessive crowding, the cam 83 is removed and replaced by another cam having a groove properly designed for the new spacing of the articles.

The admission of fluid pressure to the cylinders 34, 68, 77 and 48, for operating the arms 38 and 73 and the gripping tongs, and to indirectly effect swinging movement of the frame 22, may be in timed relation to the movement of the conveyer 15, so that one of the pairs of tongs will always be in position to pick up a bottle from the conveyer 15 as the bottles arrive, and the tongs will be operated in definite relation to the movement of the pistons in cylinders 34, 68 and 77.

In Fig. 10, I have shown a modified form of apparatus, for transferring glassware from two conveyers 15a to a leer belt conveyer 16a. In this form of apparatus, the oscillatory arms 38a and 73a, which correspond to the arms 38 and 73 of Fig. 1, are each mounted on a separate swinging frame. Arm 38a is mounted on a frame 22a and is oscillated in a vertical plane to carry ware from one conveyer 15a to the leer belt 16a, while the arm 73a is mounted on a frame 22b and is oscillated to carry ware from the other belt 15a to the leer conveyer 16a.

The frames 22a and 22b are swung about their vertical pivots, by a cam 83a that engages a roller 85a which is mounted on an extension 86a of the frame 22a, so that the arm 38a will be swung in a horizontal plane, to distribute ware across substantially one-half the width of the conveyer 16a. A link 100 connects the frame extension 86a with an extension 101 of the frame 22b, so that said frame will be oscillated about its vertical pivot, synchronously with the oscillation of the frame 22a.

The arms 38a and 73a are also swung about horizontal pivots 39a and 39b, respectively, in substantially the same manner as are the arms 38 and 73 of Fig. 1. In the present instance, however, a cylinder 34a and its piston effect reciprocatory movement of a piston

rod 32a that is connected to a cross-bar 102 whose ends are attached to chains 30a that correspond to the chain 30 of Fig. 3 and pass around sprocket wheels 29a that operate cranks 27a and 28a, to oscillate the arms 38a and 73a, through mechanism of the same character as that by which the arms 38 and 73 are oscillated.

Referring to Fig. 11, I show details of a yielding device 105 for the chains 36 and 71 of Figs. 1 and 3. The utility of the device arises from the fact that there may be failure of some of the mechanism, such as displacement of one of said chains, and one of the arms 38 or 73 may become held in a position where the other arm will be brought into contact therewith. The yielding device will permit the crank to continue its movement without damage to the apparatus, when moving in one direction. When the crank and its chain are being moved in the opposite direction by one of the pistons in cylinders 68 or 77, the fluid pressure beneath the piston possesses the requisite elasticity.

This device 105 is in the form of a cylinder that has a cap 106 which serves as a seat for a compression spring 107. A rod 108 extends through the cap 106 and has screw-threaded engagement with a turnbuckle 109 that is connected to one of the chains 36 or 71. The upper end of the rod carries a block 110 that engages the upper end of the spring 107. The cylinder 105 is connected to its chain by a block 111 that is riveted in the cylinder and serves also as a seat for 110 when the spring 107 is expanded.

The turnbuckles 109 provide means for adapting the tongs individually to operate between different receiving and discharging levels. Thus, if the turnbuckle 109 shown on Fig. 3 is lengthened, the position of the outer end of the tong arm 38 becomes lower when in the full-line position of Fig. 3, and higher when in the opposite dotted-line position. The tongs 40 may be adjusted vertically relative to the arms 38, so as to handle ware of different heights, by loosening the clamping members 43 and sliding the sleeves 41 to the desired position, after which the clamping members 43 are again tightened so as to hold the tongs in the desired adjusted position.

In order to reduce the power required for winging the tong arms, these arms may be counterbalanced by any suitable means.

In the construction shown, the cranks 27 and 28 occupy dead-center positions at their upper and lower limits of movement. In order to set these cranks in motion from their upper position, a chain 112 having a spring section 113 is provided, as shown in Figs. 2 and 3. One end of this chain is connected to the frame 22, and the other end is connected to the sprocket 29. The chain 112 is of such length that, when its point of attachment to the sprocket 29 is uppermost, the chain is

under slight spring tension, which, when the sprocket is released for reverse rotation, gives the sprocket an initial movement which brings the cranks away from dead-center position. Thereafter, the chain 112 is slack, as shown in Fig. 3, until the sprocket 29 is again rotated to extend the chain.

I claim as my invention:

1. A leer loader or stacker comprising a transfer device, means for oscillating said device about a horizontal axis to transfer ware from a receiving station to a predetermined area defining a delivery station, and means for effecting movement of said device in a horizontal plane to distribute the articles transferred. 75

2. The combination with a receiving surface of means for transferring articles thereto comprising a transfer device, means for imparting oscillatory movement to said device about a horizontal axis to transfer ware from a receiving station to said surface, and means for effecting movement thereof transversely of said surface during each cycle of the oscillatory movement. 85

3. The combination with a receiving surface of a pair of transfer devices, each device being mounted for oscillatory movement about a horizontal axis, a common actuating means for said devices, and means for effecting movement of the devices in a transverse direction during each cycle of movement thereof. 90

4. The combination with a receiving surface, of a pair of transfer devices, each device being mounted for oscillatory movement about a horizontal axis, actuating means for said devices and means for effecting a stepped movement of said devices in a transverse direction during each cycle of movement thereof, the said devices being synchronously movable in opposite directions. 100

5. A leer loader or stacker comprising a pair of transfer devices, a common means for oscillating said devices alternately about horizontal axes to effect transfer of the ware, and means for effecting movements thereof in transverse directions. 110

6. Transfer apparatus comprising an arm mounted for oscillation in a vertical plane, between a receiving station and a delivery station, tongs carried by said arm, means for operating said tongs to grasp an article when the arm is in one extreme position of movement, means for operating said tongs to release an article when the arm is in its other extreme position of movement, and means for moving said arm about a vertical axis to distribute the articles transversely of said delivery station. 115

7. Apparatus for handling glassware, comprising a transfer device, means for swinging said device about a horizontal axis between a receiving station and a delivery station to transfer ware from the former to the latter, 120

- and means for swinging said device about a vertical axis to distribute the ware transversely of said delivery station.
8. A leer loader or stacker comprising a plurality of arms, tongs mechanism carried by said arms, and means for alternately oscillating said arms about horizontal axes between a common ware-receiving point and different ware delivery points.
10. 9. A leer loader or stacker comprising a plurality of arms, tongs mechanism carried by said arms, means for alternately oscillating said arms about horizontal axes between a common ware receiving point and different ware delivery points, and means for maintaining said tongs vertically disposed during the oscillation of said arms.
20. 10. A leer loader or stacker comprising a plurality of arms, tongs mechanism carried by each of said arms, means for alternately oscillating said arms between a common ware receiving point and different delivery points, and means for opening and closing said tongs.
25. 11. In combination with a leer having a conveyer for transporting articles of glass-ware therethrough, a leer loader or stacker comprising a plurality of arms, tongs mechanism carried by each of said arms, means for alternately oscillating said arms about horizontal axes between a common ware receiving point and different delivery points, and means for oscillating said arms transversely of the leer conveyer.
35. 12. In combination with a leer having a conveyer for transporting articles of glass-ware therethrough, a leer loader or stacker comprising a plurality of arms, tongs mechanism carried by each of said arms, means for alternately oscillating said arms about horizontal axes between a common ware receiving point and different delivery points, and means for oscillating said arms in unison transversely of said conveyer.
45. 13. In combination with a leer having a conveyer for transporting articles of glass-ware therethrough, a leer loader or stacker comprising a plurality of arms, tongs mechanism carried by each of said arms, means for alternately oscillating said arms about horizontal axes between a common ware receiving point and different delivery points, and means for oscillating said arms about a vertical axis transversely of said conveyer.
55. 14. In combination with a leer having a conveyer for transporting articles of glass-ware therethrough, a leer loader or stacker comprising a plurality of arms, tongs mechanism carried by each of said arms, means for alternately oscillating said arms about horizontal axes between a common ware receiving point and different delivery points, and means for oscillating said arms in unison about a vertical axis transversely of said conveyer, each of said arms being movable over substantially one-half of the width of said conveyer, and a ratchet and pawl device driven by said arm oscillating means for imparting an intermittent motion to said cam mechanism.
60. 15. A leer loader or stacker comprising a plurality of arms, tongs mechanism carried by said arms, means for alternately oscillating said arms about horizontal axes between a common ware receiving point and different delivery points, and a parallel motion device associated with each of said tongs mechanism for maintaining said tongs vertically disposed during the oscillation of said arms.
70. 16. In combination with a leer having a conveyer for transporting articles of glass-ware therethrough, a leer loader or stacker comprising a plurality of arms, tongs mechanism carried by each of said arms, means for alternately oscillating said arms about horizontal axes between a common ware receiving point and different delivery points, and means actuated by said arm oscillating means for oscillating said arms transversely of the leer conveyer.
80. 17. In combination with a leer having a conveyer for transporting articles of glass-ware therethrough, a leer loader or stacker comprising a plurality of arms, tongs mechanism carried by each of said arms, means for alternately oscillating said arms about horizontal axes between a common ware receiving point and different delivery points, and cam mechanism for oscillating said arms transversely of said conveyer.
85. 18. In combination with a leer having a conveyer for transporting articles of glass-ware therethrough, a leer loader or stacker comprising a plurality of arms, tongs mechanism carried by each of said arms, means for alternately oscillating said arms about horizontal axes between a common ware receiving point and different delivery points, cam mechanism for oscillating said arms transversely of said conveyer, and means for imparting an intermittent motion to said cam mechanism.
90. 19. In combination with a leer having a conveyer for transporting articles of glass-ware therethrough, a leer loader or stacker comprising a plurality of arms, tongs mechanism carried by each of said arms, means for alternately oscillating said arms about horizontal axes between a common ware receiving point and different delivery points, cam mechanism for oscillating said arms in unison about a vertical axis transversely of said conveyer, each of said arms being movable over substantially one-half of the width of said conveyer, and a ratchet and pawl device driven by said arm oscillating means for imparting an intermittent motion to said cam mechanism.
100. 20. Apparatus for handling glassware, comprising a transfer arm, means for swinging said arm about a horizontal axis between a receiving station and a delivery station to

transfer ware from the former to the latter, tongs mechanism carried by said arm, means for swinging said arm about a vertical axis to distribute ware transversely of said delivery station, and means for adjusting said tongs mechanism relative to said arm to handle ware of different heights.

21. Apparatus for handling glassware, comprising a transfer arm, means for swinging said arm about a horizontal axis between a receiving station and a delivery station to transfer ware from the former to the latter, means for swinging said arm about a vertical axis to distribute ware transversely of said delivery station, and means for adjusting the limits of travel of said arm to operate between different levels.

22. A glassware handling mechanism comprising a ware carrying arm, means for supporting said arm for oscillation between a ware-receiving position and a ware-delivery position, means for oscillating said arm between said positions including a crank supported for oscillation between substantially dead center positions, a flexible connection between said crank and said arm, means for applying a turning force to said crank through its axis of oscillation to move said arm from one position to another in one direction, and the crank from an initial substantially dead center position to the other of said positions, power means operatively joined to said connection for moving said arm in a direction opposite to that in which it is moved by said crank, and to return said crank to its initial substantially dead center position, and supplemental means for assisting said last-named means in moving said crank out of said other substantially dead center position.

23. Apparatus for handling glassware, comprising means for gripping the ware, means for oscillating the first named means between a receiving station and different ware delivery points, and means for changing the path of the oscillatory movement in a horizontal plane to distribute the articles being transferred, the last named means effecting an angular movement of the second named means about a vertical axis passing through said receiving station, whereby the ware gripping means always picks up glass articles at a fixed receiving station irrespective of changes in the delivery position.

24. Transfer apparatus comprising an arm mounted for oscillation in a vertical plane, between a receiving station and different delivery stations, tongs carried by said arm, means for operating said tongs to grasp an article when the arm is in one extreme position of movement, means for operating said tongs to release an article when the arm is in its other extreme position of movement, and means for moving said arm about a vertical axis to distribute the articles trans-

versely to different delivery stations, said vertical axis, if extended, passing centrally through said receiving station.

25. In combination with a leer having a conveyer for transporting articles of glassware therethrough, a leer loader or stacker comprising a plurality of arms, tongs mechanism carried by each of said arms, means for alternately oscillating said arms about horizontal axes between a common ware receiving point and different delivery points, and means for oscillating said arms in unison about a vertical axis which is vertically aligned with said ware receiving point to effect a distribution of the ware as delivered.

26. In combination with a leer having a conveyer for transporting articles of glassware therethrough, a leer loader or stacker comprising a plurality of arms, tongs mechanism carried by each of said arms, means for alternately oscillating said arms about horizontal axes between a common ware receiving point and different delivery points, and means for oscillating said arms about a vertical axis transversely of said conveyer, said vertical axis, if extended, passing through said ware receiving point.

27. Apparatus for handling glassware comprising a pair of transfer arms, means for alternately moving said arms between a ware-receiving station and a leer conveyer, means for intermittently moving each of said arms transversely across one-half of the width of said conveyer, and means for arresting transverse movement of said arms at each end of their paths of travel in each direction to permit each arm to deposit an article upon said conveyer at the limits of their transverse movement.

28. Apparatus for handling glassware comprising a pair of transfer arms, means for moving said arms alternately between a ware-receiving station and a ware-delivery station, means for intermittently moving said arms transversely of said delivery station to distribute articles transversely thereof, and means for interrupting the transverse movement of said arms at the limits of their movement in each direction to permit each arm to deposit an article at the limits of such movement.

29. In combination with a leer having a conveyer for transporting articles of glassware therethrough, a leer loader or stacker comprising a plurality of arms, tongs mechanism carried by each of said arms, means for alternately oscillating said arms about horizontal axes between a common ware receiving point and different ware delivery points, cam mechanism for intermittently oscillating said arms transversely of said conveyer, and means for indexing said cam mechanism to move said arms in unison in steps during each of which each arm transfers an

article from said ware receiving point to a ware delivery point on said conveyer.

30. Glassware-handling apparatus comprising means for gripping articles of ware, means for oscillating said gripping means about a horizontal axis between a ware-receiving station and a leer conveyer, automatic means for moving said gripping means laterally of said conveyer in one direction to deposit articles of glassware thereon and thereafter in the opposite direction to deposit glassware in the spaces between the articles deposited in said first-mentioned movement.

15 31. Apparatus for transferring glassware from a ware receiving position to different ware delivery points, comprising a carriage mounted for swinging movement about a vertical axis, a transfer arm mounted on said carriage for swinging movement about a horizontal axis, means for swinging said carriage and said transfer arm about the said vertical axis, and means for swinging said transfer arm about said horizontal axis, said carriage, arm and all said means being disposed above the level of the ware, both at said ware receiving position and at said ware delivery points.

32. Apparatus for transferring glassware from a ware receiving position to different ware delivery points, comprising a support disposed over the ware, both at the ware receiving position and at the ware delivery points, a carriage mounted on said support for swinging movement about a vertical axis in vertical alignment with said ware receiving position, a transfer arm mounted on said carriage for swinging movement about a horizontal axis, means for swinging said carriage and said transfer arm about the said vertical axis, and means for swinging said transfer arm about said horizontal axis.

33. Apparatus for transferring glassware from a ware receiving position to different ware delivery points, comprising a support disposed over the ware, both at the ware receiving position and at the ware delivery points, a carriage mounted on said support for swinging movement about a vertical axis in vertical alignment with said ware receiving position, a transfer arm mounted on said carriage for swinging movement about a horizontal axis, means mounted on said support for swinging said carriage and said transfer arm about said vertical axis, and means mounted on said carriage for swinging said transfer arm about said horizontal axis.

34. Apparatus for handling glassware, comprising an arm mounted for oscillatory movement about a horizontal axis, takeout tongs pivotally mounted on said arm, a sprocket wheel mounted in fixed relation coaxially with the axis of swing of said arm, a sprocket wheel mounted on said tongs and

in fixed relation thereto, and a sprocket chain connecting said sprocket wheels and adapted to maintain said tongs vertically disposed throughout the swinging movement of said arm.

35. Transfer apparatus comprising an arm mounted for angular oscillation about an axis to transfer glassware between two horizontally spaced points, tongs carried by said arm, means for operating said tongs to grasp an article when the arm is in one extreme position of its angular movement, means for operating said tongs to release an article when the arm is in its other extreme position of movement, a pivotal supporting member for said tongs, and chain and sprocket means for rotating said member about its pivot in predetermined relation to the oscillatory movements of said arm.

Signed at Hartford, Conn., this 8th day of July, 1926.

EDWARD H. LORENZ.
